(57) **CLAIM**

The ornamental design for a display screen with graphical user interface, as shown and described.

DESCRIPTION

The FIGURE is a front view of a display screen with graphical user interface showing our new design in the environment of a handset.

The broken lines of the display screen with graphical user interface showing the environment in the FIGURE and the unshaded regions therein are for illustrative purposes only and form no part of the claimed design.

1 Claim, 1 Drawing Sheet
